US00D578128S

(12) **United States Design Patent**
Lee et al.

(10) **Patent No.:** **US D578,128 S**
(45) **Date of Patent:** **** Oct. 7, 2008**

(54) **DOCKING DEVICE**

(75) Inventors: **Shih-Yun Lee**, Chungho (TW);
Jung-Wen Chang, Tao Yuan Shien
(TW); **Chun-Yu Chen**, Luchou (TW)

(73) Assignee: **Quanta Computer Inc.**, Tao Yuan Shien
(TW)

(**) Term: **14 Years**

(21) Appl. No.: **29/267,943**

(22) Filed: **Oct. 26, 2006**

(30) **Foreign Application Priority Data**

Jul. 5, 2006 (TW) 95303777

(51) **LOC (8) Cl.** **14-02**

(52) **U.S. Cl.** **D14/433; D14/434**

(58) **Field of Classification Search** D14/240,
D14/242, 356, 358, 363, 365, 367, 370, 432–437,
D14/439; D13/147, 164, 123, 133, 146,
D13/110, 199, 103, 162, 159, 160, 184; 361/683,
361/684, 686, 724, 735, 737, 752

(57) **CLAIM**

The ornamental design for a docking device, as shown and described.

DESCRIPTION

FIG. 1 is a perspective view of a docking device showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.
